US00D958490S

(12) United States Design Patent (10) Patent No.: US D958,490 S
(45) Date of Patent: * Jul. 26, 2022

(54) UNDERWEAR

(71) Applicant: PATENTMANIAC CONSULTING,
New Delhi (IN)

(72) Inventors: Nitin Pal, New Delhi (IN); Jatinder Kumar, New Delhi (IN)

() Term: 15 Years

(21) Appl. No.: 29/716,087

(22) Filed: Dec. 6, 2019

(51) LOC (13) Cl. 02-01

(52) U.S. Cl.

USPC D2/712

(58) Field of Classification Search

USPC D2/712-716, 728-738, 742-748;
D24/124, 126

See application file for complete search history.

(57) CLAIM

The ornamental design for underwear, as shown and described.

DESCRIPTION

FIG. 1 is a front perspective view of underwear showing the new design, shown in an open configuration;

FIG. 2 is a front view of an open configuration thereof;

FIG. 3 is a back view of an open configuration thereof;

FIG. 4 is a left view of an open configuration thereof;

FIG. 5 is a right view of an open configuration thereof;

FIG. 6 is a top view of an open configuration thereof;

FIG. 7 is a bottom view of an open configuration thereof;

FIG. 8 is a front perspective view of the Underwear shown in a closed configuration;
FIG. 9 is a front view of a closed configuration thereof;
FIG. 10 is a back view of a closed configuration thereof;
FIG. 11 is a left view of a closed configuration thereof;
FIG. 12 is a right view of a closed configuration thereof;
FIG. 13 is a top view of a closed configuration thereof; and,
FIG. 14 is a bottom view of a closed configuration thereof.
